UNITED STATES PATENT OFFICE.

WEBB JAY, OF CHICAGO, ILLINOIS.

HEATING APPARATUS FOR CARBURETERS.

1,291,532.

Specification of Letters Patent. Patented Jan. 14, 1919.

Application filed May 11, 1914. Serial No. 837,924.

To all whom it may concern:

Be it known that I, WEBB JAY, a citizen of the United States, residing at Chicago, in the county of Cook and State of Illinois, 5 have invented certain new and useful Improvements in Heating Apparatus for Carbureters, of which the following is a specification.

My invention relates to heating apparatus 10 for carbureters adapted to be used in connection with automobile engines, or the like. It is well known that after an automobile has been standing idle and the parts thereof become cold great difficulty is often experienced in starting the engine again, owing to the failure of the fuel to vaporize readily and form an explosive mixture with the air drawn into the carburetor. This difficulty is especially marked in cold weather and 15 causes great annoyance until the engine and associated parts have become thoroughly heated. A further difficulty is presented by the rapid decrease in the available supply of gasoline and the increased cost thereof, 20 which makes it desirable to use as fuel some of the heavier hydrocarbons, such as kerosene. These heavier fuels are less volatile than gasoline, and do not vaporize so readily. Consequently, it is substantially 25 impossible to start or continue to run an engine on these fuels, even in warm weather, unless means be provided for preheating the fuel and the mixture in the carburetor.

One method which has been tried is that 30 of causing the exhaust gases from the engine to circulate about the mixing chamber of the carburetor, thereby tending to heat the contents thereof. An apparatus embodying this principle obviously will not aid in the starting 35 of the automobile before any exhaust gases have been formed, and it has been found that such a device is irregular and unsatisfactory after the starting of the engine.

I have therefore provided means whereby 40 the air drawn into the carbureting chamber is heated independently of the exhaust gases. My device is very economical, and may usually be operated from the fuel supply for the 45 lighting system. The degree of heat may be maintained uniform at all times, or adjusted to different values by means readily accessible to the operator. A means is further provided for heating the contents of the carbureting chamber after a mixture has been 50 formed therein so that the explosive quali-

ties thereof are greatly increased before being drawn into the engine cylinders. A further object of my invention is to arrange the heating elements so that they may also act 60 as a foot-warmer for the operator.

Other objects will be set forth and made apparent in the following specification taken in connection with the accompanying drawings, in which—

Figure 1 shows a side elevation of my improved heating apparatus assembled on an automobile, which is shown in dotted lines.

Fig. 2 is a perspective view of the forward portion of the automobile showing the relative position of certain parts of my apparatus.

Fig. 3 is a longitudinal section taken through the forward portion of the automobile, showing a side elevation of my heating 75 apparatus with certain parts thereof in section; and

Fig. 4 is a vertical section through the burner.

Like numerals refer to like parts and elements in the several figures of the drawings, in which the automobile comprises a body 10, a hood 11, engine 12, dash 13, and foot-board 14. These parts form no part of my invention, and are shown merely as a basis 85 for describing the application of my improved heating apparatus.

Referring to Fig. 3, the carburetor 15, which is located adjacent the engine 12, comprises the float chamber 16, the carbureting 90 or mixing chamber 17, and the valve chamber and inlet duct 18. The carbureting chamber has a flange 19 at the upper portion thereof, by means of which a connection is made to the intake manifold which leads to 95 the engine cylinders. A water-jacket chamber 20 is formed around the carbureting chamber and is provided with an inlet duct 21, through which water may be introduced to the interior thereof. This duct is closed 100 by a plug 22, and an air escape valve 23 is provided in the upper wall of the water-jacket chamber so that the air in said chamber may escape as the water is introduced thereto.

The air inlet duct 18 is connected, by means of a pipe 24, with the heating chamber 25, the walls of which are preferably lined with heat-insulating material. A valve 24^a is provided in this pipe 24 adjacent the 110 chamber 25, to permit the introduction of fresh air into said pipe. The heating cham-

65

80

105

110

ber comprises side walls 26 and 27 and upper and lower walls 28 and 29, respectively. The side wall 27 is secured to the dash 13. This chamber is so located that the upper wall 28 is flush with the upper surface and forms a part of the foot-board 14, as shown clearly in Fig. 2. The lower wall 29 is provided with apertures 30 therethrough, which serve as inlets to the chamber 25. The wall 26 of said chamber is hinged along its upper edge, as shown at 31, and is maintained in closed position by the spring 32.

A gas burner 33 is located beneath the lower wall of the chamber 25, and is provided with the usual valve 34, by means of which the air supply to the burner may be regulated. The valve 34 seats upon the cap 35, which closes the lower end of said burner and which is apertured at 36 to permit a connection to the fuel supply. A flanged sleeve 37 is secured to the burner above the valve 34, and has seated thereon the cup member 38, which is adapted to receive and closely fit the cylindrical flue chamber 39. This flue chamber projects upwardly through an aperture in the lower wall of the chamber 25, and has an annular flange 40 formed on the upper end thereof, which seats upon the upper surface of the wall and forms a tight connection therewith. A supply of fuel gas is contained in the tank 41, from which a pipe 42 leads to the valve 43, which is located beneath the hood 11 on the forward side of the dash 13. A handle 44 of the valve 43 projects through the dash in a position where it may be conveniently reached by the operator. A return pipe 45 passes from the valve 43 to the burner 33, where it projects through the aperture 36 in the cap member 35 and forms a tight connection therewith.

The following means is provided for lighting the burner: A hard rubber, or other insulating block 46 is seated upon the upper surface of the cup member 38 around the burner 33, and has secured thereto an upwardly projecting metal terminal 47, which has an in-turned point 48 just above one edge of the burner. An insulated conductor 49 is connected to the terminal at the point 50, and passes through the cup member to a battery 51. The other terminal of the battery is connected by means of the insulated conductor 52 to an electric switch 53, which is located on the dash adjacent the valve handle 44. The other terminal of the switch 53 is connected by means of the insulated conductor 54 to the pipe 45. It is apparent that this pipe forms an electrical connection between the switch and the burner, so that when the switch is closed an electric spark will pass between the point 48 of the terminal 47 and the upper portion 35^a of the burner, thereby igniting the gas which discharges from the burner.

65 A water tube or pipe 55 is connected to the

lower portion of the water jacket chamber 20 at the point 56, and is led into the heating chamber 25 at the point 57. This tube is coiled in spiral form directly above the outlet of the flue chamber 39, and the other 7 end of said pipe passes from the upper portion of the chamber 25 at the point 58 and communicates with the upper portion of the water-jacket chamber at the point 59. It is thus apparent that the heating of the 75 spiral portion 55^a of the tube 55 will cause a circulation of water through the water jacket chamber.

The operation of my device is as follows: The operator turns the handle 44 of the 80 valve 43, thereby introducing fuel gas under pressure to the burner 33. The switch 53 is then operated to close the electric circuit and cause a spark to pass between the point 48 and the point 35^a on the burner, 85 thereby lighting the said burner and causing the chamber 25 to be heated to a degree depending upon the adjustment of the valves 43 and 34. The wall 26 of the chamber 25 is hinged so that if an explosion occurs upon 90 the ignition of the gas discharged from the burner 33, said wall will swing outwardly to release the pressure within the chamber and prevent breakage of any of the parts thereof. The chamber 25 being heated, it is 95 apparent that fresh air drawn in through the apertures 30 will pass through the pipe 24 to the mixing chamber 17 of the carburetor. The heated air drawn into the mixing chamber with the charge of fuel from the 100 float chamber will cause said fuel to volatilize readily to form an explosive mixture in the mixing chamber. As previously described the heating of the coil 55^a will cause a circulation of hot water through the pipe 105 55 and the water jacket chamber 20; so that the chamber 17 will be heated independently of the hot air which is drawn into said chamber through the inlet duct 18. This additional heating of the contents of the chamber 110 17 will form a very highly explosive mixture therein before said mixture is drawn by suction through the intake manifold to the cylinders of the engine. It is further apparent that the location of the chamber 25 115 is such that it may be conveniently used as a foot warmer in cold weather, since the air therein and the walls thereof will be highly heated by the burner 33. When it is desired to produce a relative variation in the temperature of the air drawn in through the inlet duct 18 without altering the temperature of the water within the water jacket chamber, the valve 24^a may be adjusted to introduce fresh cold air directly into the pipe 120 24. A simultaneous variation in the heat of the air within the pipe 24 and of the water within the chamber 20 may be made by regulating the burner 33 through the agency of the valves 34 and 43. 125 130

While I have described my invention in connection with the operation of an automobile, it will of course be apparent that it may be embodied in other structures which are adapted for different purposes and that my invention may be embodied in other forms of apparatus without departing from the spirit thereof as defined by the appended claims.

5 10 I claim:—

- 11 1. In an automobile having a dash and a foot board, a carbureter having a carbureting chamber and located adjacent said dash, a heating chamber mounted beneath said foot-board and adjacent said dash, an air duct connecting said heating and carbureting chambers, and means to heat said heating chamber.
- 12 2. In a device of the class described, a carbureter having a carbureting chamber and a water jacket chamber around said carbureting chamber, a heating chamber having air inlets in the walls thereof, a supply of fuel, a burner arranged beneath said heating chamber to heat the air therein, an air duct leading from said heating chamber to said carbureting chamber, and a water pipe leading through said heating chamber and having each end thereof communicating with said water jacket chamber.
- 13 3. In an automobile, a carbureter having a carbureting chamber and a water jacket

chamber around said carbureting chamber, a heating chamber having air inlets in the walls thereof, said heating chamber being 35 mounted adjacent the dash of said automobile, a supply of fuel, a burner arranged beneath said heating chamber to heat the air therein, an air duct leading from said heating chamber to said carbureting chamber, 40 and a water pipe leading through said heating chamber and having each end thereof communicating with said water jacket chamber.

4. In an automobile, a dash, a carbureter, 45 a heating chamber adapted to supply heated air to said carbureter, a burner adapted to heat the interior of said heating chamber, a supply of fuel, a pipe leading from said fuel supply to said burner, said pipe 50 having a valve therein, said valve being located with the handle thereof projecting through said dash, an electric ignition system adapted to light said burner, and a switch to operate said system, said switch 55 being located on said dash adjacent the handle of said valve.

In testimony where of, I have subscribed my name.

WEBB JAY.
